UNITED STATES PATENT OFFICE.

WILLIAM P. J. HAGARTY, OF AVON, SOUTH DAKOTA.

CIGARETTE CASE.

1,407,746.

Specification of Letters Patent. Patented Feb. 28, 1922.

Application filed June 24, 1920. Serial No. 391,424.

To all whom it may concern:

Be it known that I, WILLIAM P. J. HAGARTY, a citizen of the United States, residing at Avon, in the county of Bon Homme and State of South Dakota, have invented 5 certain new and useful Improvements in Cigarette Cases; and I do hereby declare the following to be a full, clear, and exact description of the invention, such as will enable others skilled in the art to which it 10 pertains to make and use the same.

The present invention relates to a case for carrying cigarettes or other similar articles in the pocket, and aims to provide a novel 15 and improved container of that kind.

It is the object of the invention to provide a case having an endless belt therein provided with grooves or similar means for receiving and holding the cigarettes or articles, and means for mounting or moving the belt whereby the cigarettes can be brought 20 one at a time in succession to a slot or opening for removal from the case.

It is also the object of the invention to 25 provide a device of the character indicated which is comparatively simple and inexpensive in construction, as well as being convenient and efficient in use.

With the foregoing and other objects in 30 view, which will be apparent as the description proceeds, the invention resides in the construction and arrangement of parts hereinafter described and claimed, it being understood that changes can be made within 35 the scope of what is claimed without departing from the spirit of the invention.

The invention is illustrated in the accompanying drawing, wherein:—

Figure 1 is a perspective view of the im- 40 proved case.

Fig. 2 is a longitudinal section on the line 2—2 of Fig. 1.

The case proper, designated 5, can be 45 made of sheet metal or other suitable material and finished in any preferred way, being of a width to accommodate cigarettes of the desired length and the case can be of any length desired, according to the capacity wanted. Parallel shafts 6 are mounted 50 for rotation in the edge portions of the case 5 adjacent to the ends thereof, and have rollers 7 thereon within the case around which an endless belt 8 of rubber or other suitable material extends to move along the 55 opposite sides and ends of the case. The outer surface of the belt has integral trans-

verse ribs 9 forming transverse grooves or receptacles 10 for receiving and holding the cigarettes 11, or other articles, and a knob 12 is secured to one end of one of the shafts 60 6 for turning the corresponding roller 7, whereby to move the belt. The edges of the ribs 9 are narrow or thin and such ribs increase in thickness from said edges to their bases so that the grooves between them are 65 concaved transversely thereof to snugly receive the cigarettes. One end of the case 5 has a slot 13 past which the grooves 10 move in succession when the belt is moved, thereby bringing the cigarettes 11 one at a time 70 in succession to the slot or opening 13 for removal. Said slot is preferably provided with finger and thumb notches 14 between its ends for convenience in lifting the cigarette out of the groove 10 and slot 13. Said 75 slot 13 is preferably at one end of the case, with the knob 12 adjacent to said slot for convenience in manipulating the device.

For convenience in placing the cigarettes within the case, it is preferable to have one 80 side, designated 15, hinged, as at 16, at that end opposite to the slot 13 so that said side 15 can be swung open, thereby exposing one half or run of the belt, so that the cigarettes can be readily placed within the grooves 10. 85 The belt can then be moved to move said half or portion thereof to the opposite side, so that the remaining half can be filled, after which the side 15 is swung closed. The side 15 can be held closed by any suit- 90 able means, such as by an ear 17 extending from one or both edges to overlap and engage the edge portion of the case frictionally, although other suitable means can be used for this purpose. 95

When a cigarette is removed through the slot 13, the remaining cigarettes are retained in the case against accidental loss therefrom, and when a cigarette is wanted the knob 12 is simply turned until a cigarette is brought under the slot 13, when it can be readily removed therefrom. The cigarettes are thus retained in the case, and are only brought to position for removal one at a time in succession, thereby avoiding 100 the spilling or loss of the cigarettes, and affording convenient means for dispensing the cigarettes. The cigarettes are retained in the grooves 10 which confront the sides and ends of the case inasmuch as the walls of the 105 case keep the cigarettes from falling from said grooves, the cigarettes moving along 110

said walls. The cigarettes are held snugly between the ribs 9 by friction, and it will be noted that where the belt extends around the rollers 7, the bending of the belt will 5 separate the ribs 9, thereby loosening the cigarettes where they pass around the rollers at the ends of the case. Therefore, by having the slot 13 located at one end of the case beyond the corresponding roller 7, 10 the cigarettes are loosened adjacent to said slot, so that they can be readily removed through the slot.

Having thus described the invention, what is claimed as new is:—

15 A device of the character described, comprising a flat case, rollers mounted in the

case adjacent to the ends thereof, means for turning one roller, and an endless belt of rubber or similar material extending around 20 said rollers and having transverse ribs on its outer surface forming grooves for snugly holding cigarettes or similar articles to be moved with the belt, said ribs being separated slightly at the points where the belt extends around the rollers, the case having 25 a transverse slot at one end beyond one roller for removing the cigarettes or articles.

In testimony whereof I have signed my name to this specification.

WILLIAM P. J. HAGARTY.
